UNITED STATES PATENT OFFICE.

CONRAD ADAMI, OF BOSTON, ASSIGNOR TO JAMES W. TUFTS, OF MEDFORD, MASSACHUSETTS.

SODA-WATER-DISPENSING APPARATUS.

SPECIFICATION forming part of Letters Patent No. 439,923, dated November 4, 1890.

Application filed April 23, 1890. Serial No. 349,164. (No model.)

To all whom it may concern:

Be it known that I, CONRAD ADAMI, a citizen of the United States, residing at Boston, in the county of Suffolk and State of Massachusetts, have invented certain Improvements in Soda-Water-Dispensing Apparatus, of which the following is a full, clear, and exact description, reference being had to the accompanying drawings, making part of this specification, in which—

Figure 1 is a perspective view of a soda-water-dispensing apparatus constructed in accordance with my invention, the top of the casing being removed to show the interior of the ice-chamber. Fig. 2 is a longitudinal vertical section of the same. Fig. 3 is a transverse vertical section of the same. Fig. 4 is a perspective view of one of the sirup-cans removed from the apparatus. Fig. 5 is a view 20 of one of the covering-plates detached.

My invention relates to that description of soda-water-dispensing apparatus in which the sirup-cans are adapted to slide in and out from the front of the casing and in which the 25 fronts of the said cans are concealed from view by covering plates or doors placed thereover. With this construction it has hitherto been necessary to partially draw out the sirup-cans from their chamber when they require to be filled, to avoid which is the object of my invention, which consists in hinging or pivoting the lower edge of the covering-plate which conceals the front of the can to the sirup gate or faucet instead of to the front 35 of the casing, whereby the sirup-can may be made of such shape that its front upper corner will project into a position to allow of the can being filled through a suitable aperture at said upper front corner without moving it 40 from its place within the chamber, as herein-after set forth.

My invention also consists in providing the sides of the metal ice box or chamber with air-spaces having inlet-apertures communicating 45 with the interior of the ice-chamber and outlet-apertures leading into the chamber beneath, which contains the sirup-cans, whereby cold air is permitted to pass from the ice-box directly into the can-chamber for the purpose of cooling the sirup within the cans, as

desired; and my invention also consists in a device for preventing the swash or sudden movement of the sirup from one end of the can to the other in case it should be found necessary to carry it in the hands from one 55 place to another; and my invention furthermore consists in certain novel combinations of parts and details of construction, as herein-after set forth, and specifically pointed out in the claims.

In the said drawings, A represents the outer casing of the apparatus, composed, as usual, of marble or other suitable material. Within the upper portion of the casing is fitted the removable metallic ice box or chamber B, 65 provided, as usual, with a waste-pipe b, and adapted to contain coolers C, connected by pipes a with the fountain, (not shown,) said coolers being also connected by pipes c with the draft-tubes D at the front of the casing. 70 Beneath the ice-box B, the ends of which rest on ledges or shoulders 10, is a space or chamber E for containing the long narrow sirup-cans G, which are arranged side by side and adapted to slide in and out of the chamber E 75 through the front of the casing, which is left open at d for this purpose. The floor or bottom e of the chamber E is inclined downward toward the front to permit the water produced by condensation to flow into a longitudinal groove or depression 12, from which it escapes by a waste-pipe f, leading into the waste-pipe b.

To the casing in front of the can-chamber E is secured a series of narrow metallic strips g, bent into curved or ogee form and placed one on each side of each can G at such distance apart as to allow of the passage of a can between each pair of strips. Between the strips g and the back 25 of the metallic 85 casing extend a series of flat guide-bars k, which are inclined so as to be parallel with the downwardly-sloping bottom e of the chamber E. These bars k, which are of greater width than the strips g, so as to extend on 90 each side of the same, are adapted to fit into longitudinal grooves i, formed on the opposite sides of the sirup-cans G at or near the center and extending from one end to the other, as seen in Fig. 4, the cans under this 100

arrangement being easily slid in and out upon the guide-bars with very little friction, and being held firmly and steadily in place without liability of being tipped to one side or 5 the other when the faucets are being turned. Moreover, with this construction no partitions are required between the cans to keep them in place, while the guide-grooves in said cans are easily and cheaply made and add little or 10 nothing to the cost of the can, especially if it is made of glass or porcelain.

Each can G is provided at the bottom of its front end with a gate or faucet H, permanently secured thereto and serving as a handle, by 15 means of which the can may be slid in and out of the chamber E, a projection o on the under side of the neck of the gate or faucet hooking over the edge of a plate 17, secured to the front of the apparatus, whereby the 20 can is locked in place when pushed into the can-chamber E to its full extent, it being merely necessary to slightly raise the front end of the can to clear the projection o from the edge of the plate 17 when it is desired to 25 draw out the can from its chamber. Immediately above the neck of the faucet H the front of the can is inclined forward and upward, forming an overhanging portion or extension k', at the top of which is an opening 30 m, through which the can is filled, the front portion of this opening extending a little beyond the front of the marble casing A, when the can is in place, to permit the sirup to be introduced without drawing out the can 35 or disturbing it from its normal position.

The opening m is provided with a covering-plate n, which is hinged on one side to the top of the can to enable it to be thrown back, as seen in Fig. 4, when the can is drawn out 40 of its chamber and it is desired to uncover the entire opening. The hinge, however, is constructed to allow the covering-plate n when shut down over the opening m to slide back and forth in the direction of its length on the 45 pintle or pin p of the hinge as far as allowed by the portions 15 16 of the hinge, which serve as stops, whereby when the can is in place within the chamber the plate n can be slid or pushed back a short distance without lifting 50 it on its hinge to uncover the front end of the opening m, as seen at the right-hand side of Fig. 1, sufficiently to allow of the can being filled, as required, without moving it from its normal position, which is a great advantage, 55 as it can be kept cooler if allowed to remain constantly within the chamber. Moreover, by hinging the cover the liability of its loss in the operation of washing or cleaning the apparatus is avoided.

60 The front of each can G when in place within the chamber E is concealed from view by an ornamental covering-plate J, which is hinged at its lower edge to the rectangular portion q of the neck of the sirup-gate H, so 65 that it may be dropped down into the position seen at the right-hand end of Fig. 1 when it is desired to gain access to the opening m

at the top of the can. The plate J can be detached from the gate H by simply sliding it to the left-hand side, the joint resembling an ordinary door-hinge in this respect, and said plate J is maintained in its upright position to conceal the front of the can by a spiral or other suitable spring r, secured at one end to the plate and at the other end to the neck of the faucet, the spring being also so arranged as to draw the plate J laterally inward toward the stationary portion 18 of the hinge to prevent it from becoming accidentally detached at the joint. The spring r can be detached 80 or unhooked at either end, when desired, to remove the plate J, and when said plate is drawn down to its full extent, so as to rest on the front end of the gate, as seen in Figs. 1 and 4, it will remain in such position until 85 again raised by hand, as the spring r will not then exert a pressure in the direction necessary to raise it to an upright position. In the upper side of the can near its front end is formed a narrow slot s, extending transversely 90 across the can from side to side, and within this slot is fitted a sliding partition-plate t, which is adapted to be dropped down into the position seen in Fig. 3, the plate being of the same width as the can and extending down 95 nearly to the bottom thereof. This plate when down practically shuts off the greater portion of the sirup from the front end of the can and serves to prevent the swash or sudden movement of the sirup from one end of the can 100 to the other while it is being carried in the hand from place to place, it being an exceedingly difficult matter to carry an elongated can of this description in a perfectly horizontal position, and if not so carried the weight of the sirup 105 is such that a very slight tipping of the can toward the front end will cause a sudden movement of the entire body of sirup in that direction, which would result in an overflow or spilling of the same from the opening m, 110 through which the can is filled. This is entirely prevented by the employment of the partition-plate above described, which, as it does not reach the bottom of the can, does not interfere in the least with the free flow of the 115 sirup to the gate or faucet H when the can is in place within the apparatus.

At the rear end of the can G, near its top, is an aperture provided with a liquid-tight screw-cap u, this aperture when open greatly 120 facilitating the washing out of the can, as a free outlet is afforded for the water at each end, together with an opportunity to introduce a swab or other cleaning implement, if desired.

125 The ice box or chamber B is made double at each end, as seen in Fig. 2, whereby air-spaces w are formed, said spaces having inlet-apertures a' at the top opening into the ice-chamber and outlet-openings b' at the bottom communicating with the sirup-can chamber E, whereby the cold air from the ice-chamber is caused to pass therefrom through the apertures a', air-spaces w, and discharge-

5 apertures *b'* into the can-chamber for the purpose of cooling the sirup-cans and their contents as desired, thus utilizing the ice to the greatest possible extent and cooling the can-chamber more rapidly and effectually than can be accomplished with the construction hitherto in common use.

What I claim as my invention, and desire to secure by Letters Patent, is—

- 10 1. In an apparatus for dispensing soda-wa-
ter, &c., the combination, with a sirup-can
having a gate or faucet projecting from its
front end and adapted to be slid in and out
of the can-chamber through the side of the
apparatus, of a covering-plate hinged at its
lower edge to the sirup gate or faucet, and a
device for holding said covering-plate in an
upright position when swung upward on its
hinge, substantially as described.
- 15 2. In an apparatus for dispensing soda-wa-
ter, &c., a sirup-can provided at its front end
above the sirup gate or faucet with a project-
ing or overhanging portion extending out be-
yond the plane of the front of the outer casing
when the can is in place and having an open-
ing at the top of its front upper corner
through which the can may be filled, in com-
bination with a covering-plate hinged at its
lower edge to the gate or faucet, and a spring
30 for holding said covering-plate in an upright
position to conceal the front of the can, sub-
stantially as set forth.
- 20 3. In an apparatus for dispensing soda-wa-
ter, &c., the combination, with the sirup-can
35 and its gate or faucet, of a covering-plate
hinged at its lower edge to the said gate or
faucet and adapted to be detached therefrom
by a lateral movement, as described, and a
spring adapted to draw the said plate later-
ally inward and also hold it in place when
40 swung up into an upright position to conceal
the front of the can, substantially as set forth.
- 4. In an apparatus for dispensing soda-wa-

ter, &c., the combination, with the can-cham-
ber provided with a series of guide-bars *k*, 45
extending from the front to the rear end of
the same and rigidly secured at their opposite
ends, of a series of horizontally-sliding sirup-
cans provided on their opposite sides with
longitudinal guide-grooves *i*, extending from 50
the front to the rear ends of the same and
adapted to slide horizontally in and out of
the can-chamber upon said guide-bars *k*, sub-
stantially as set forth.

5. In an apparatus for dispensing soda-wa- 55
ter, &c., the combination, with a horizontally-
sliding sirup-can having an extension at its
front end projecting beyond the plane of the
front of the outer casing and provided with
a filling-opening *m* at the top of its front 60
upper corner, of a covering-plate *n*, hinged
to the side of the opening *m* and adapted
when shut down to slide in the direction of
its length to uncover the front end of said
opening *m* to permit of the introduction of 65
the sirup into the can without moving the
same, substantially as set forth.

6. In an apparatus for dispensing soda-wa- 70
ter, &c., the combination, with an elongated
horizontally-sliding sirup-can, of a movable
partition-plate *t*, adapted to slide vertically
through a slot or opening *s* in the top of the
can and extending nearly to the bottom of
the same when forced down, whereby a space
is left between the lower end of the partition-
plate and the bottom of the can to permit the
sirup to flow freely from one end of the can
75 to the other and the swash or spilling of the
sirup prevented while the can is being car-
ried in the hand, substantially as set forth. 80

Witness my hand this 19th day of April,
A. D. 1890.

CONRAD ADAMI.

In presence of—

P. E. TESCHEMACHER,
G. W. MC LAUGHLIN.
